RAMON V. DIXN, OF PLYMOUTH, MICHIGAN, ASSIGNOR, BY MESNE ASSIGNMENTS, TO
ROY G. MICHELL, OF DETROIT, MICHIGAN

COMBINATION SHIPPING AND DISPLAY BOX

Application filed October 20, 1930. Serial No. 489,861.

This invention relates to a combination shipping and display box.

In the merchandising field it is very common to openly display such things as tooth paste, tooth brushes, cigarettes, medicines, candy, and the like. This custom has long since created a need for a box in which any of these articles can both be shipped and displayed. Various types of box structures have been used to tilt the upper layer of tubes, cigars, or whatever merchandise is being sold to better display the same and attract the customer's eyes. These various box structures have in many instances been very complex and/or costly which rendered them commercially impractical because a box of this type is not designed to be used more than once. Hence, simplicity in structure and cheapness in production have become very important items in this art. It is more particularly with this type of combined shipping and display box that this invention is concerned.

It is the object of this invention to produce a combined shipping and display box which comprises a container having a top which may be opened and an end having an opening therein, and an insert for the said container which serves as a closure for the opening in the end of the container when the same is used as a shipping box and which may be tilted, when the container is used as a display box, to display a portion of the merchandise and to open the opening in the end of the container so that the merchandise removed from the tilted insert, as it is being sold, can be replenished by withdrawing merchandise from the inside of the casing through the opening in the rear end.

In the drawing:

Fig. 1 is a perspective view showing the combined shipping and display box when used as a shipping case.

Fig. 2 is a perspective view of the same box when used for display purposes.

Fig. 3 is a detail plan view of the insert.

Fig. 4 is a side elevation of the insert.

Figs. 5 and 6 are front and side elevations of the insert when the box is used as a shipping box as shown in Fig. 1.

Figs. 7 and 8 are front and side elevations of the insert when the box is used as a display case as shown in Fig. 2.

In the drawing there is shown an outer container 1 having a top 2. This container is preferably made of cardboard although it is understood that it can be made of wood, sheet metal, and the like. Further, the container 1 is preferably a collapsible container so that it can be shipped flat but it can also be what is known as a "set-up container", that is, one which is shipped already set up. The container 1 is shown as a set-up container for convenience in description only since this eliminates many lines in the drawing which would tend to detract from the clearness of the disclosure.

The container 1 consists of the front wall 3, the rear wall 4, the side walls 5, the bottom 6, and the cover 2. As shown the cover 2 is hinged to the rear wall 4 as at 7 and has a flap 8 along the forward edge thereof which fits along the inside of the upper edge of the front wall 3 when the cover 2 is closed as shown in Fig. 1. It is understood that the container 1 could be provided with any suitable cover since the invention is not dependent upon the type of cover used for the container 1.

The rear wall 4 of the container is provided with an opening 9. This opening preferably extends from the bottom of the rear wall, that is, from the junction of the rear wall 4 with the bottom 6 upwardly a sufficient distance to permit the withdrawal of whatever articles of merchandise positioned within the container. The width of the opening 9 is likewise determined by the size of the articles of merchandise contained within the container.

The container 1 is provided with an insert shown specifically in Figs. 3 to 8. This insert consists of a front flap 10, shelf portion 11, and a rear flap 12. The flaps 10 and 12 are hinged to the shelf 11 along the lines 13 and 14. The rear flap 12 is provided with a pair of ears 15. The flaps 10 and 12 may be of the same or different dimensions, which dimensions vary according to the type of ar-

ticles which are arranged to be displayed in the combined shipping and display box 1.

For descriptive purposes only, the container 1 is shown of a size sufficient to accommodate 12 boxes of tooth paste, three tiers of four each. Such a tooth paste box

5 is shown at 16. The container 1 in this instance is loaded with eight boxes such as shown at 16, four abreast and two tiers high.

10 The insert is then placed in the container 1 so that the front flap 10 is flush against the inner face of the front 3 of the container. The bottom edge of the flap 10 rests upon the bottom 6 of the container 1. The rear flap

15 12 is placed flush against the inside face of the rear wall 4 of the box 1 so that the bottom edge of the flap 12 rests upon the bottom 6 of the box. At this time the rear flap 12 serves as a closure for the opening 9. The shelf 11 is parallel to the bottom 6 of the container 1 when, as shown, the flaps 10 and 12

20 are of the same size. The ears 15 rest flush against the inner faces of the side walls 5 of the container. Since the insert is preferably 25 of cardboard and the ears 15 are an integral part of the insert flap 12 there will be a certain amount of spring action to the flaps 12 when they are bent to the position shown in Fig. 1.

30 After the box has been partially loaded and the insert positioned as shown in Fig. 1 the final tier of boxes 16 are placed upon the shelf 11. This final tier of boxes will be flush with the upper edges of the container.

35 At this time the cover 2 is closed, as shown in Fig. 1, and the box may be used for shipping purposes. When it is desired to display the goods for sale purposes, the top of the cover 2 can be removed or opened as

40 shown in Fig. 2. At this time the flap 12 may be slid upwardly so that the opening 9 is opened and the shelf 11 is tilted to the position shown in Figs. 2, 7, and 8. At this time the ears 15, owing to their spring action,

45 spring outwardly as soon as they clear the upper edge of the sides 5, and hence, by engaging the upper edge of the sides 5, maintain the shelf 11 in tilted position and thusly the merchandise boxes 16 are very nicely displayed owing to their tilted position.

50 Sales can be made from the upper tilted tier of boxes resting on the shelf 11. The merchandise on the inclined shelf 11 can be replenished by withdrawing merchandise from within the container 1 beneath the shelf 11

55 through the opening 9. It is evident that the rear flap 12 serves as a closure for the opening 9 when in lowered position, as a handle for raising the shelf 11 to tilted position, and also as a support for the shelf 11 and the merchandise supported thereby.

60 It is evident from the above description that there is here produced a combined shipping and display case, one end of which 65 has an opening therein, and an insert for the

container which serves as a closure for the opening when the box is used for shipping purposes and as a tilted display shelf for the merchandise when the box is used for display purposes.

70

I claim:

1. A combined shipping and display box for merchandise and the like comprising in combination a container having an opening in a wall thereof, an insert for the said container having a shelf portion and a flap portion, the flap portion being arranged to slidably engage within the said container and in one position serving as a closure for the said opening and arranged to be slid to open the said opening and to tilt the shelf portion to better display the merchandise and permit removal of the merchandise from within the container through the said opening to replenish merchandise removed from the tilted shelf.

75

80

2. A combined shipping and display box for merchandise and the like comprising in combination a container having an opening in a wall thereof, an insert for the said container having a shelf portion and a flap portion, the flap portion being arranged to slidably engage within the said container, in one position serving as a closure for the said opening and arranged to be slid to open the said opening and to tilt the shelf portion to better display the merchandise and permit removal of the merchandise from within the container through the said opening to replenish merchandise removed from the tilted shelf, and means integral with the said flap for retaining the shelf in tilted position.

85

3. A combined shipping and display box for merchandise and the like comprising in combination of a container having an opening in a wall thereof, an insert for the said container having a shelf portion and a flap portion, the flap portion being arranged to slidably engage within the said container, in one position serving as a closure for the said opening and arranged to be slid to open the said opening and to tilt the shelf portion to better display the merchandise and permit removal of the merchandise from within the container through the said opening to replenish merchandise removed from the tilted shelf, and one or more spring ears carried by the said flap within the said container and arranged to spring outwardly as the flap is slid upwardly to tilt the shelf to engage the upper edge of the box to retain the shelf and flap in raised position.

90

100

4. A combined shipping and display case comprising a container having an opening in the rear wall thereof, an insert for the said container having a shelf portion and a flap portion, the flap portion serving as a slideable closure for the said opening and as means for raising the shelf to a tilted position to better display the merchandise car-

105

ried by the said shelf, a pair of spring ears carried by the said flap arranged to engage the inside of the said container when the flap closes the said opening, and arranged to engage the upper edge of the said box when the flap and shelf portion are raised upwardly to retain the said shelf and flap portion in raised position.

5. A combined shipping and display box comprising in combination an outer container having an opening therein, an insert consisting of front and rear flaps and a shelf portion, the flaps being hinged to the said shelf portion, the said flaps being of less height than the walls of the said container, one of said flaps serving as a slidable closure for the opening in the wall of said container, and the other flap resting on the bottom of the said container and serving as a hinge support for the said shelf portion of the insert whereby the closure flap can be slid upwardly to open the said opening and to tilt the shelf.

10 In testimony whereof I affix my signature.
